UNITED STATES PATENT OFFICE

WADE H. BUSH, OF UNIVERSITY CITY, MISSOURI

DESIGN FOR AN ELECTRICAL FIXTURE

Application filed January 26, 1933. Serial No. 47,002. Term of patent 7 years.

To all whom it may concern:

Be it known that I, WADE H. BUSH, a citizen of the United States, and a resident of University City, St. Louis county, Missouri, have invented a new, original, and ornamental Design for an Electrical Fixture, of which the following is a specification, reference being had to the accompanying drawing, forming part thereof, in which is shown a perspective view of a fixture embodying the invention.

I claim:

The ornamental design for an electrical fixture, as shown.

In testimony whereof, I have signed my name to this specification this 24th day of January, 1933.

WADE H. BUSH.
